No. 783,700.

PATENTED FEB. 28, 1905.

E. E. MILLER.
ATTACHMENT FOR HORSE BLANKETS.
APPLICATION FILED MAY 13, 1904.

UNITED STATES PATENT OFFICE.

EDWARD E. MILLER, OF NEW HAMPTON, IOWA.

ATTACHMENT FOR HORSE-BLANKETS.

SPECIFICATION forming part of Letters Patent No. 783,700, dated February 28, 1905.

Application filed May 13, 1904. Serial No. 207,875.

To all whom it may concern:

Be it known that I, EDWARD E. MILLER, a citizen of the United States, residing at New Hampton, in the county of Chickasaw and 5 State of Iowa, have invented a new and useful Attachment for Horse-Blankets, of which the following is a specification.

My object is to provide a simple device for detachably fastening a blanket on a horse to 10 the traces when the horse is hitched to a vehicle in such a manner that the blanket will be retained securely in proper position over the back and body of the horse.

My invention consists in the construction 15 and application of an attachment to a blanket, as hereinafter set forth, pointed out in my claims, and illustrated in the accompanying drawings, in which—

Figure 1 is a central sectional view of a 20 spherical weight that is adapted to be used in lieu of a buckle on a strap for fastening the blanket to a harness-trace, and Fig. 2 is a corresponding view taken on the line *x x* of Fig. 1. Fig. 3 shows a blanket on a horse fastened 25 to the harness as required in practical use. Fig. 4 is an enlarged detail view showing a strap connected with a harness-trace and securely fastened thereto by means of the spherical weight on the lower free end of the strap. Fig. 5 shows a modified way of retaining the 30 weight on the strap.

The numeral 10 designates a cover or blanket 35 on a horse, and 12 a flexible strap, preferably leather, fixed on the outside of the rear portion of the blanket by riveting or stitching. The end portions of the strap are passed through openings in the blanket, so that they will depend on the inside of the blanket.

A weight, preferably a round metal ball 13, 40 is slidably connected with the free end portions of the straps 12, (only one of them is shown,) as indicated by dotted lines in Fig. 4. The weights have transverse open-ended slots for the passage of the straps, and the slots are 45 enlarged to produce chambers for leaf-springs 14 and shoulders 15 at the ends of the chambers to engage the ends of the springs, as required to prevent the springs from getting

out of the chambers. The springs can be readily pressed through the open ends of the 50 slots into the chambers and the straps then passed through the slots to be engaged by the springs, as indicated by dotted lines in Fig. 4, to be clamped fast and slidably connected with the straps. To prevent the weights from 55 slipping off the straps, a piece of leather or button 16 is riveted on the end of the strap, as shown in Fig. 4, or a wire 17 may be coiled and fastened on the strap, as shown in Fig. 5.

To detachably fasten the blanket on a horse 60 by means of my invention, it is only necessary to lift the corners of the blanket and double the free end portions of the strap 12 around the harness-traces, as shown in Fig. 3. The weights 13 will then by force of gravity retain 65 the straps fastened to the traces, and to free the straps it is only necessary to lift the weights and pass them inward over the traces.

Having thus set forth the purpose of my 70 invention and its construction, application, and operation, the practical utility thereof will be readily understood by persons familiar with the use of horse-blankets; and

What I claim as new, and desire to secure 75 by Letters Patent, is—

1. In an attachment for horse-blankets, a weight having a transverse open-ended slot, shoulders in the slot and a leaf-spring in the slot in engagement with said shoulders, in combination with a strap fixed to the rear end portion of a horse-blanket, said strap being passed through said slot in the weight and engaged by said spring as shown and described, for the 80 purposes stated.

2. An attachment for a horse-blanket consisting of a flexible strap fixed across the rear end portion of the blanket and the free end portions of the strap extended through the blanket and downward and weights connected with the free end portions of the strap to operate in the manner set forth for the purposes 85 stated.

EDWARD E. MILLER.
